CONVERTIBLE COUCH

Edward Frank, Long Beach, Calif.

Application August 25, 1958, Serial No. 52,368

Term of patent 14 years

(Cl. D15—11)

Fig. 1.

Fig. 2.

Fig. 3.

Figure 4 is a front elevational view of said couch with the back folded downwardly and the seat cushions placed upon the folded back;

I claim:

The ornamental design for a convertible couch, substantially as shown and described.
